UNITED STATES PATENT OFFICE.

CHARLES H. TUCKER, OF JORDAN, NEW YORK.

HERNIAL TRUSS.

SPECIFICATION forming part of Letters Patent No. 240,479, dated April 19, 1881.

Application filed January 28, 1881. (Model.)

To all whom it may concern:

Be it known that I, CHARLES H. TUCKER, of Jordan, in the county of Onondaga, in the State of New York, have invented new and useful Improvements in Hernial Trusses, of which the following, taken in connection with the accompanying drawings, is a full, clear, and exact description.

The nature of this invention consists in certain improved means for adjustably connecting the pad to the main supporting plate or arm of the truss.

The invention is fully illustrated in the accompanying drawings, wherein Figure 1 is a back view of my improved truss; Fig. 2, a longitudinal section on line $\alpha\alpha$ in Fig. 1; and Figs. 3 and 4 are side and rear face views, respectively, of the pad proper and the supplemental pad connected therewith.

Similar letters of reference indicate corresponding parts.

A denotes the plate or arm, designed to hold the pad P in its requisite position over the hernia. Said arm is adjustably connected to the usual waistband by means of a plate or bar, a , which is provided at opposite ends with suitable means for the attachment of the band, and has a longitudinal slot, through which a screw, b , passes, said screw also passing through a longitudinal slot, c , in a bar, d , on the arm A , and is provided on its end with a nut, n , which is countersunk in a groove in the back of the bar d , and engages ledges or ways e at the sides of the slot c . The screw b serves both as a pivotal and a clamp screw, and, in conjunction with the slotted bars a and d , affords the necessary adjustability of the position of said arm in relation to the band. The arm A is clamped in its desired position by tightening the set-screw b , and is further secured by means of a plate, f , which is pivoted in the slot c of the bar d , and has a segmental slot, g , through which a clamp-screw, h , passes, said screw having a nut, n' , which rides on the ways e at the back of the bar d , before described. The plate f has its edge adjacent to the plate a serrated or corrugated, to engage with corresponding serrations or corrugations on the edge of the plate a , and thus effectually prevents slipping of the latter.

In order to make the plate a reversible end

for end, and thus adapt it for either side of the abdomen, I provide both edges of the said plate with the aforesaid serrations or corrugations.

55

The ledges or ways e , on which the nuts n n' ride, are inclined from the ends of the slot c toward the center thereof, thereby producing upon the nuts, when tightened, a wedging action, which crowds them toward each other, 60 and thus overcomes all danger of the plates a and f working loose.

The bar d is placed lengthwise the arm A , and connected thereto by trunnions i on the extremities of the former passing through journal-bearings k on the latter, so that the arm is allowed to turn and accommodate itself to the movement of the person wearing the truss. The trunnion on the lower end of the bar d has a projecting-prong, s , to which is hinged a bar, 65 l , which, in turn, is hinged on the pad P by a pintle passing transversely through said bar l . The end of the prong s has on its under side a hook or notch, m , which engages the top of a nut, o , on a set-screw, p , inserted through the 70 top of the bar l , and in conjunction with another set-screw, q , applied to the lower or opposite end of the bar l and bearing on the back of the pad, prevents the base of the pad from yielding to outward pressure. By proper manipulation of the set-screws p and q the base 75 of the pad can be set at any desired angle to the plane of the arm A and adjusted to bear on the hernia with greater or less pressure.

The top portion of the pad is yieldingly 80 pressed inward or toward the abdomen by means of a spring, v , interposed between the upper end of the bar l and upper part of the pad. This feature of holding the pad against the hernia by a rigid or unyielding support on 85 the base of the pad and a yielding support at the upper part thereof is one of the chief peculiarities of my invention, as by that means the hernia is more effectually retained than by a pad supported yieldingly at its base, as has 90 heretofore been customary.

R represents a supplemental pad applied to the base of the pad P , for the purpose of arresting the viscera which may accidentally escape from underneath the pad P proper, said 95 pad R being connected to the pad P by means of a spring-plate, r , secured to the back of the

pad P by a screw, t, and having at the base of said pad a forward bent portion, u, on which the supplemental pad R is pivoted.

Having described my invention, what I claim is—

1. In combination with the supporting plate or arm A, the reversible plate a, serrated or corrugated at its two longitudinal edges, and the plate f, having a correspondingly serrated or corrugated edge, and the clamping-screws b and h, applied respectively to said plates, substantially as described and shown.

2. In combination with the plates a and f and their clamping-screws b and h, having nuts n and n', the bar d, provided with the slot c, and the centrally-inclined ways e, substantially as described, for the purpose set forth.

3. In combination with the plate a and arm A, the bar d, having trunnions i in bearings k on the arm A, substantially as shown and set forth.

4. A hernial truss provided with a firm or unyielding support for the base of the pad and with a yielding support for the top of the pad, substantially as set forth.

5. The combination, with the arm A, of the bar d, provided with the prong s, having hook m, and the pad P, hinged to said prong, and having a set-screw, p, provided with a catch 30 for engaging the hook m and limiting the

swinging movement of the pad in one direction, substantially as described.

6. In combination with the arm A, the bar d, having a prong, s, provided with the hook m, the bar l, pivoted to the pad and to the 35 prong s, and provided with the screw p, nut o, and set-screw q, substantially as described and shown.

7. In combination with the arm A, the bar d, connected to said arm, and having a prong, 40 s, provided with hook m, the pad P, bar l, pivoted to the pad and to the prong s, the screw p, having nut o, the set-screw q, and the spring v, all combined and operating substantially in the manner set forth.

8. In combination with the pad P, the plate r, having the bend u, the set-screw t, and the pad R, pivoted on the bent portion u, all substantially as shown and described, for the purpose set forth.

In testimony whereof I have hereunto signed my name and affixed my seal, in the presence of two attesting witnesses, at Syracuse, in the county of Onondaga, in the State of New York, this 15th day of January, 1881.

CHAS. H. TUCKER. [L. S.]
